(73) Assignee: **Plastiflex Canada Inc.**, Orangeville, Ontario (CA)

Primary Examiner—Mark A Goodwin

(**) Term: **14 Years**

CLAIM

(21) Appl. No.: **29/347,206**

The ornamental design for an electrical receptacle and inlet valve faceplate, as shown and described.

(22) Filed: **Oct. 23, 2009**

DESCRIPTION

(30) **Foreign Application Priority Data**

Aug. 13, 2009 (CA) 131822

FIG. 1 is a front perspective view of a first embodiment of an electrical receptacle and inlet valve faceplate showing our new design in use condition;

(51) **LOC (9) Cl.** 11-05

FIG. 2 is a front elevational view thereof;

(52) **U.S. Cl.** D8/353

FIG. 3 is a rear elevational view thereof;

(58) **Field of Classification Search** D8/350-353;

FIG. 4 is a left side elevational view thereof;

D13/156, 177, 152, 154, 158, 173, 169, 171,
D13/139.1-139.8, 146, 147; D14/159; D25/60;

FIG. 5 is a right side elevational view thereof;

174/66, 67; 220/241, 3,92, 3.5-3.8, 242;

FIG. 6 is a top plan view thereof;

439/536, 535, 892; 200/303; 248/273; 292/357

FIG. 7 is a bottom plan view thereof;

See application file for complete search history.

FIG. 8 is a front perspective view thereof shown in open condition;

(56) **References Cited**

FIG. 9 is a front perspective view of a second embodiment of an electrical receptacle and inlet valve faceplate showing our new design in use condition;
